UNITED STATES PATENT OFFICE

ANTONIOS G. KATSOUNAKIS, OF STEUBENVILLE, OHIO

DESIGN FOR A GARTER OR SIMILAR ARTICLE

Application filed December 6, 1929. Serial No. 33,674. Term of patent 7 years.

To all whom it may concern:

Be it known that I, ANTONIOS G. KATSOUNAKIS, a citizen of Greece, and resident of Steubenville, county of Jefferson, and State of Ohio, have invented a new, original, and ornamental Design for a Garter or Similar Article, of which the following is a specification, reference being had to the accompanying drawings, in which the single figure is a perspective view of a garter or similar article, showing my new design.

I claim—

The ornamental design for a garter or similar article, as shown.

ANTONIOS G. KATSOUNAKIS.
